UNITED STATES PATENT OFFICE.

CLAYTON E. FREDERICKSON, OF CHICAGO, ILLINOIS.

INTERNAL-COMBUSTION ENGINE.

1,232,524.

Specification of Letters Patent. Patented July 10, 1917.

Application filed May 29, 1916. Serial No. 100,498.

To all whom it may concern:

Be it known that I, CLAYTON E. FREDERICKSON, a citizen of the United States, residing at Chicago, in the county of Cook and State of Illinois, have invented new and useful Improvements in Internal-Combustion Engines, of which the following is a specification.

This invention relates to improvements in internal combustion engines, and more particularly to the multi-cylinder, four cycle type of internal combustion engine, designed, as to its general features of construction, in accordance with the usual practice.

One improved feature of the invention pertains to the valve mechanism, wherein it is proposed to employ the reciprocating piston type of valve, together with certain features of construction calculated to reduce the leakage of the gas through the valves, to decrease the friction in the working parts, and to otherwise promote the efficient and dependable operation of the engine.

Another feature of the invention is the incorporation in an internal combustion engine of a novel method for utilizing the heat of the burned gases in the heating of the explosive mixture, prior to its entrance into the combustion chamber of the engine cylinder. In ordinary practice this is accomplished by the provision of auxiliary heating devices utilizing the heat of the engine for the purpose of increasing the temperature of the air which enters the carburetor and is mixed with the hydrocarbon fluid to form the explosive mixture. For reasons that will be hereinafter fully set forth, it is proposed to heat the hydrocarbon gas after the mixture has taken place, allowing the mixture to be effected with the air at substantially atmospheric temperature, rather than heating the air prior to entering the carburetor and there being combined with the hydrocarbon vapor. It is therefore one object of the invention, not only to incorporate this method of treating the mixture in an internal combustion engine, but to provide a novel construction for utilizing the heat of the burned gas in the most efficient manner.

The features of the invention hereinbefore referred to, together with others, will be now

described in detail and in connection with the accompanying drawings, in which—

Figure 1 is a view in side elevation of an internal combustion engine or motor embodying the features of my invention, with parts thereof broken away to show parts within;

Fig. 2 is a view in vertical section through the cylinder and inlet valve of the engine;

Fig. 3 is a view in vertical section through the cylinder and exhaust valve of the engine;

Fig. 4 is a view in horizontal section of the engine taken on line 4—4 of Fig. 2; and

Fig. 5 is a detail sectional view taken on line 5—5 of Fig. 2, showing the timing gears for driving the valve crank shaft from main crank shaft.

Referring more in detail to the construction of the engine embodying the features of the invention, the same comprises a plurality of cylinders 10, formed integral with each other, said cylinders numbering four, as shown, although for the purpose of this invention the number of cylinders is immaterial. As a preferable construction, the cylinders are cast integral or "en bloc" and are, together with the valve mechanism, surrounded or inclosed by a casing 11. The outer wall 12 of the casing is spaced from the walls of the cylinders and valves and forms therebetween a space 13, commonly known as a water jacket, there being also provided a space or water jacket between the several cylinders and valves, in order that the surfaces may be cooled by the circulation of water through said jacket. Suitable water connections (not shown) are provided for supplying water to and removing it from the water jacket. Rigidly connected to the lower margin of the cylinder casing 11 is a crank case 14, secured in the usual manner by means of bolts 15 and forming a chamber communicating with the lower ends of the cylinders and within which are contained the crank shaft 16, crank shaft bearings, and associated parts. As shown in Figs. 1 and 2, the crank case is preferably made in two parts to permit the easy removal of the same and access to the interior thereof.

Within each of the cylinders is mounted a reciprocating piston 17, preferably of the

hollow, single acting type and provided with the usual arrangement of piston rings 18. Connecting the several pistons with the cranks 19 of the crank shaft 16 are the connecting rods 20, journaled to the piston at their upper ends and to the main crank shaft 16 at their lower ends, by the provision of the usual type of apertured bearings, which engage the transverse pins 17^a of the 10 piston and the crank pin 19^a of the crank 19, respectively. The crank shaft extends longitudinally of the crank case and is rotatively mounted in suitable bearings, the several cranks 19 being relatively displaced 15 in angular relation, according to the usual practice, in order to effect a uniform transmission of power from the several cylinders to the crank shaft. The upper portion of the cylinder forms the combustion chamber, 20 there being provided, in the upper wall of each cylinder, a threaded aperture, within which is mounted a spark plug 21, adapted to perform the usual function, in conjunction with other parts of a suitable ignition 25 system, of igniting the charge within the combustion chamber at predetermined intervals.

Associated with each cylinder and extending parallel therewith are two vertical 30 cylinders or cylindric chambers arranged side by side and extending throughout the entire height of the cylinder casing 11. These cylinders constitute the valve chambers of the engine, and are termed the inlet 35 valve chamber 22 and the exhaust valve chamber 23. Referring to Fig. 4, it will be noted that the arrangement of the valve chambers is reversed in alternating cylinders; in other words, in the two cylinders 40 on the left (Fig. 4) the inlet valve chambers 22, 22 are adjacent to each other and are located between the associated exhaust valve chambers 23, 23, and, in the same manner, the two cylinders on the right have 45 a similar arrangement of the valve chambers, namely, the inlet valve members are arranged adjacent to each other and intermediate their associated exhaust valve chambers. The purpose of grouping the valve 50 chambers in this manner is to facilitate the admission of explosive gas to the several inlet valve chambers 22, 22, as will be understood from the following: An intake manifold 24 conducts the gas from a single 55 intake connection 25 at its central portion (Figs. 1 and 4), delivering the same at points midway between the end cylinders 10 and their adjacent cylinders, the discharge openings of said manifold communicating 60 with smaller or branch manifolds 26 preferably located within the cylinder casing 11 and formed integral therewith, said branch manifolds having a central inlet opening and serving to again divide the 65 flow of the gas and deliver it to the adjacent

valve chambers, through ports or intake openings 27, 27 (Fig. 2) formed in the outer wall of said inlet valve chambers. The inlet and exhaust valve chambers communicate with their respective cylinders by means of 70 inlet and exhaust cylinder ports 28 and 29, respectively, said cylinder ports extending transversely of the cylinders and adjacent to the upper end thereof. It is to be noted, with regard to the cylinder ports, that the 75 exhaust ports 29 are located somewhat below the inlet ports 28 (Figs. 2 and 3), and, furthermore, the inlet and exhaust ports are arranged parallel and in laterally spaced relation, as clearly shown in Fig. 4. 80

Within each of the valve chambers 22, 23, respectively, are mounted the inlet valve members 30 and exhaust valve members 31. These valve members, as is common in engines of this type, are operated from the 85 main crank shaft 16 by the arrangement of members as follows: A counter or valve crank shaft 32 is rotatively mounted in the crank case, adjacent and in parallel relation to the main crank shaft. At one end of 90 the engine, preferably the forward or right-hand end (Figs. 1 and 5), the main crank shaft 16 and valve crank shaft 32 extend or project through the wall of the crank case and are provided at their ends with intermeshing gear wheels 33 and 34, respectively 95 (Fig. 5), the former being of smaller diameter than the latter, or valve crank shaft gear wheel 34. The diametric relation or ratio expressed numerically is 2 to 1, or, in other words, the valve crank shaft is rotated through one revolution during two revolutions of the main crank shaft. These gear wheels are preferably inclosed within a casting 35, fastened by means of bolts to the 100 wall of the crank case 14. The valve crank shaft is provided with a plurality of pairs of cranks 36 and 37, each pair being associated with one of the cylinders. To the 105 crank pins of each pair of said valve cranks 36 and 37 are journaled the inlet valve connecting rod 38 and exhaust valve connecting rod 39, respectively, said rods being journaled at their upper ends to their associated 110 inlet and exhaust valve members 30 and 31 by means of integral cross pins 40 and 41, respectively. As shown in Fig. 5, the cranks 36 and 37 are arranged in spaced relation and on either side of the associated 115 crank 19 of the crank shaft 16. Inasmuch as the several cranks of the main crank shaft are angularly displaced, it follows that the several pairs of valve cranks are correspondingly displaced in angular relation. Furthermore, the valve cranks 36 and 37 of 120 each pair are angularly displaced relatively to each other, the amount of relative angular displacement in this instance being predetermined by the timing or travel of the 125 valves as governed by the sequence of events 130

of the associated cylinders. As shown in Figs. 2 and 3, wherein are illustrated the crank positions of the inlet and exhaust valves of a single cylinder, the crank shafts 5 are displaced from each other through an angle of substantially 90°.

Inasmuch as the valve mechanism of each cylinder is identical with the valve mechanism of every other cylinder, a detail description of one will suffice for all. Referring now to Figs. 2 and 3, the inlet and exhaust valve members 30 and 31 are cylindric in shape and of the hollow or sleeve type, having a central passage surrounded by a 15 cylindric wall. The valve members are open at their ends and are provided with transverse partition walls 42 and 43, which divide the passages of the respective inlet and exhaust valve members into two parts, the upper 20 part forming the working or valve proper of the members. The partition walls 42 and 43 are located substantially midway of the length of the valve members, although it is to be noted that the partition wall 42 25 of the inlet valve member is located somewhat lower than the wall 43 of the exhaust valve member, thus providing in the former a longer passage at its upper end. Furthermore, the inlet valve member is slightly 30 longer than the exhaust valve member, and the connecting rod 38 of said inlet valve member is slightly shorter than the rod 39 of said exhaust valve member. In essential 35 features of construction both the inlet and exhaust valves may be said to be similar, although differing somewhat in detail, as will now be pointed out. Referring now to the inlet valve member 30, the same is provided, immediately above the partition 40 wall 42, with a port 44 formed in the wall of the valve and located so as to register with and open and close the intake opening 27, which communicates with the discharge opening of the branch manifold 26. 45 As a desirable means for packing the valve to prevent leakage, a plurality of piston rings are provided, which surround the upper end portion of the valve member, said piston rings being preferably arranged in 50 pairs 45 and 46, one pair, 45, being mounted in closely spaced relation adjacent to the upper end of the valve, and the other pair, 46, being mounted adjacent to but below the first mentioned pair, and, with relation to 55 the width of the cylinder port 28, the distance separating the pairs of piston rings is substantially twice the longitudinal width of said port. The purpose of this particular arrangement of the piston rings will be understood from the following. As shown in 60 Fig. 2, for instance, the port 28 is closed by the valve member, and the piston rings are so disposed with relation to the port that one pair of piston rings 45 is located immediately above the port, and the other pair 46

is located a slightly greater distance below the port. This arrangement, therefore, provides a packing on both sides of the port, thus preventing the escape of the gas through the port and along the surface of 70 the valve member in either direction. Furthermore, the rings are located in close proximity to the port, thus making the sealing of the port exceedingly effective. The effect of leakage and loss of compression in 75 the cylinder upon the performance and efficiency of internal combustion engines is too well known to require further comment.

The inlet valve member 30 travels with a reciprocating movement substantially 80 throughout the length of the valve chamber, and, with respect to the cylinder port 28, the valve travel is such that the upper edge of the valve member passes above the port and completely covers it in its upward movement, and on the downward movement of the valve the upper edge passes a short distance below the port, thus uncovering the port and opening communication between the valve chamber and the cylinder. Likewise, in the travel of the valve, the intake opening is alternately opened and closed by the passage of the port 44 into and out of register therewith, thus admitting the mixture at proper intervals into the interior 85 passage of the valve member. It is obvious, therefore, that the explosive mixture is conducted from the carburetor to the cylinder through the manifolds 24 and 26; through the intake opening 27; into the valve member 90 30, by means of the port 44; upwardly through the valve member and valve chamber, and thence into the cylinder through the port 28. 95

Referring now to the arrangement of the 105 exhaust valve 31, as clearly shown in Fig. 3, the same is constructed in substantially the same manner as the inlet valve just described, being provided with pairs of piston rings 47 and 48, which are arranged, with 110 respect to each other and to the exhaust port 29 of the cylinder, in substantially the same manner and for the same purpose as hereinbefore described in connection with the inlet valve. The exhaust valve member is also 115 provided with a port 49, formed in its wall immediately above the partition wall 43 and adapted to register with the exhaust port 29 of the cylinder. As before, the exhaust valve member travels with a reciprocating 120 movement, alternately opening and closing the exhaust port 29 by the registering therewith of the valve port 49. In this respect, the operations of the two valves are reversed, inasmuch as the cylinder port is not uncovered by the end of the valve as in the inlet valve, but by the registering of the port 49, as described. Furthermore, the gases are exhausted through the upper end of the valve chamber into an exhaust pipe or mani- 125 130

fold 50, which will be more completely described elsewhere.

There are certain other features common to both inlet and exhaust valves, which may now be described. In the walls of both the inlet and exhaust valve cylinders are formed annular channels 22^a and 23^a, respectively, said channels being preferably located in the plane of the respective inlet and exhaust ports 28 and 29 of the cylinder. These channels are somewhat less in width than the piston rings 39 and 42 and form a space completely surrounding the valves when the same are in a position to close the respective inlet and exhaust ports. The function of these channels is to permit the pressure of the gas within the cylinder to be exerted upon all points of the valves, particularly at the instant of explosion, and in this manner equalize the force exerted by the pressure and to thereby reduce the friction which would otherwise be increased, by reason of the increased pressure exerted on the port side of the valve members, which would tend to force them against the opposite side of the cylinder wall.

Closely associated with the valve mechanism described are the means hereinbefore referred to whereby the heat of the exhaust gases is utilized for preheating the explosive gas, prior to entering the cylinder. Referring to Figs. 2 and 3, it is to be noted that the upper ends of the valve chambers are open, and, furthermore, all of these openings are arranged in longitudinal alignment along one side of the engine (Fig. 4). Extending over these openings and secured to the top of the cylinder casing is the exhaust pipe or manifold 50, the same being provided with laterally extending flanges 51, through which suitable bolts extend, thereby rigidly securing the manifold in place. Arranged along the under surface of the manifold are a plurality of outlet connections 52 (Fig. 1), arranged at right angles to the main passage of the manifold and registering with the upper ends of the exhaust valve chambers 23. As shown in Figs. 1 and 2, the lower wall of the manifold is flat and covers the openings of the inlet valve chambers 22, forming the closure or top wall thereof. Along the lower wall of the manifold are provided a plurality of vertically depending tubes 53, closed at their lower ends and so positioned along the manifold that a tube 53 projects downwardly into each of the inlet valve chambers 22 and arranged in axial alignment therewith. These tubes, or "hot heads" as they are called, are preferably formed integral with the manifold and communicate with said manifold at their upper ends. The tubes extend downwardly into the valve chambers 22 substantially one-half the length thereof and so, also, project into the

passage of the valve member 30, terminating just short of the path of movement of the partition wall 42 of the valve member 30. The walls of the tubes or "hot heads" are preferably reduced in thickness and terminate in a rounded extremity, which is completely closed. The diameter of the tubes or "hot heads" is preferably uniform and somewhat less than the diameter of the passage in the valve members, thereby providing an annular space or passage surrounding the "hot head" and through which the gas passes.

The purpose of these so-called "hot heads" is to conduct a portion of the burned gases as they pass through the exhaust manifold downwardly into the passage of the inlet valve, the heat thus transmitted to the walls of the "hot heads" by the constant circulation of the hot gases therethrough serving to increase the temperature of the comparatively cool mixture that flows upwardly through the space surrounding the "hot heads" and in contact with the heated walls thereof. As a result, therefore, the temperature of the mixture is increased to a degree sufficient to effect the complete breaking up of the hydrocarbon elements and to promote the uniform and homogeneous mixture of the air and hydrocarbon vapor. The construction of the manifold and "hot head" herein described provides an exceedingly simple, yet efficient method of conducting the hot gases directly into the inlet valve chambers, in that the gases are utilized immediately after they are exhausted, hence the maximum temperature obtained in the "hot heads." The arrangement of valve chambers and particular type of valve used, further, assures the practical and efficient application of the "hot head" method of heating the mixture.

Having described in detail the several features of construction embodying my invention, the coöperation of the same to produce an efficient engine will be better understood from the following description of the operation of the engine: In Figs. 2 and 3 the inlet and exhaust valve members may be assumed to be in the positions which they occupy at the instant a charge of the mixture is ignited in the cylinder, that is, the piston is at the beginning of its downward stroke, and the main crank shaft assumed to be rotated in a clockwise direction and the valve crank shaft to be rotated in the opposite or counterclockwise direction, as indicated by the arrows. In the positions shown, the inlet and exhaust ports 28 and 29 are closed by their respective valve members, it being particularly noted that the pairs of piston rings are disposed on opposite sides of the port. As is clearly seen from the crank positions of the valves, the inlet valve is approaching the upper extremity of its

travel as the piston begins its downward stroke, but, inasmuch as the valve crank shaft is at this instant rotating in a counter-clockwise direction and through the upper 5 arc of its path, the travel of the valve is its minimum, therefore the inlet port 28 is not opened or uncovered by the valve until the piston has completed its upward or exhaust stroke and the intake or suction stroke about 10 to begin. On the other hand, the exhaust valve 29 at the commencement of the power stroke is just beginning its upward travel, and its crank is entering upon its arc of maximum throw, hence the travel of said 15 exhaust valve is rapid, so that at the beginning of the exhaust stroke the exhaust port 29 is opened by the registration of the valve port 49 therewith, and the burned gases escape through the valve into the exhaust 20 manifold. At the completion of the exhaust stroke the exhaust valve begins to close, its crank having passed through the upper arc 25 of its path of movement, and enters upon its downward arc of maximum throw, thus moving the valve rapidly and closing the exhaust port in an exceedingly short interval of time, said exhaust port remaining closed during the intake, compression, and power strokes of the piston, and at the same 30 time completing its upward and downward stroke preparatory to again opening the exhaust port at the beginning of the following exhaust stroke. The inlet valve is timed in a similar manner, so that during the compression, power, and exhaust strokes of the 35 piston the inlet valve 28 remains closed, and uncovers the same at the commencement of the inlet stroke and covers it again at the end thereof and just before the commencement 40 of the compression stroke.

Particular attention is to be called to the relation of the valve, cylinder ports, and crank positions as the several events in the cylinder occur as above described. In the 45 first place during period in which the valve members are moving at minimum velocity, that is, when the cranks are passing through the arcs adjacent to the upper and lower dead centers, the valves are in positions to 50 close the inlet and exhaust ports. Manifestly, it is particularly desirable that leakage be eliminated so far as possible during the compression and power strokes, inasmuch as the power available is dependent to 55 a large degree upon the pressure obtained within the cylinder. Now, since the valves are timed so that their travel is least during the events when maximum pressure is desired, it is possible to arrange the piston 60 rings upon the valve members so that during the closed positions of the inlet and exhaust ports the travel of the valves is practically confined to the distance separating the pairs of piston rings, thus the inlet and exhaust 65 ports are effectively sealed to prevent leak-

age, by the presence of at least one ring on both sides thereof, which are spaced sufficiently close together to obtain effective results.

Among the advantages secured by the 70 particular construction and arrangement of the valves as described and illustrated, is the advent of a practical application of the piston or sleeve type of valve, in that they are timed to secure rapid opening and closing of 75 the ports at the proper instant with relation to the cycle of events in the cylinder, and at the same time securing the most effective results in the use of the piston ring type of packing, namely, by arranging them upon 80 the piston in relation to the ports so as to reduce the leakage and loss of compression to a minimum, yet avoiding the excessive amount of friction which is present in most 85 types of piston and sleeve type of valves, in order that the elimination of leakage may be secured.

One reason, among others, for the superior performance of an engine embodying the so-called "hot head" construction, is due 90 not only to the particular construction employed, but also to the fact that it embodies a departure from the ordinary practice of heating the air prior to introducing it into the carburetor, where it is combined with 95 the liquid hydrocarbon. The chief objections to the usual method are based upon the well known physical property of air, namely, expansion under the influence of heat, and, further, for the reason that in 100 carburetors as constructed the air enters or is drawn into the mixing chamber thereof through an opening that is permanent in size and cannot be adjusted to meet the constantly varying conditions of the atmosphere and operation of the engine. Those 105 familiar with the construction and operation of internal combustion engines are well aware that the purpose of heating the air is to facilitate the rapid and complete vaporization of the liquid hydrocarbon, by breaking up the hydrocarbon elements so that they may combine more freely with the air and thus produce a more uniform and homogeneous mixture, which is capable of delivering 110 an impulse of greater force when ignited within the explosion chamber of the cylinder. It is well known that air when heated, not only expands, but its density is decreased in proportion, thus if heated air 115 is introduced into a carburetor, it is obviously of less density than the air at atmospheric temperature, although the actual amount or volume of air supplied to the carburetor is constant, owing to the constant size 120 of the orifice through which it enters. The decreased density of the air effects a corresponding decrease in the capacity of the air to combine with the hydrocarbon fluid, and as a result the heated air does not combine 125 130

with or support as much of the hydrocarbon vapor as would the same volume at a lower temperature. It is manifest that in each charge entering the cylinder there is a smaller proportion of the hydrocarbon vapor per unit volume, hence the power produced by the charge upon ignition is decreased. On the other hand, if the mixture takes place between air at normal or atmospheric temperature and the hydrocarbon vapor, every unit volume of air carries or combines with a maximum amount of hydrocarbon. Each charge entering the cylinder is, therefore, capable of delivering a maximum impulse when ignited. The fact that the mixture is expanded by the subsequent heating in contact with the "hot head" does not, however, diminish the effectiveness of the charge, because the proportion of hydrocarbon and air remains constant, or, in other words, the initial mixture being accomplished under conditions of maximum air density, the subsequent heating does not decrease the power that may be delivered by a single charge, since the effect of heating is to further expand the hydrocarbon elements as well as the air and thus maintain the balance between the constituents of the gas.

30 For the reason set forth, therefore, increased power and efficiency are secured by heating the mixture immediately before it enters the carburetor, without otherwise affecting the purpose accomplished by the heat, in the treatment of the explosive hydrocarbon gas.

The features of my invention may obviously be modified as to the details of construction, without departing from the spirit 40 of the invention, and for this reason I do not wish to be limited to the construction herein described and illustrated except in so far as set forth in the appended claims.

I claim as my invention:

45 1. An internal combustion engine, comprising a cylinder, a piston within said cylinder, inlet and exhaust passages communicating with said cylinder, a valve associated with said inlet passage, and a member mounted within said inlet passage intermediate said valve and cylinder and adapted to be heated by the gases exhausted from said cylinder.

2. An internal combustion engine, comprising a cylinder, a piston within said cylinder, inlet and exhaust passages communicating with said cylinder, a hollow valve member within said inlet passage, and a tubular member communicating with said exhaust passage and extending into the interior of said valve member.

3. An internal combustion engine, comprising a cylinder, a piston within said cylinder, an inlet passage provided with an intake opening and communicating with said

cylinder through a port spaced from said intake opening longitudinally of said passage, an exhaust passage communicating with said cylinder for conducting the burned gases from said cylinder, and a tubular member communicating with said exhaust passage and extending into said inlet passage beyond said port and terminating adjacent to said intake opening.

4. An internal combustion engine, comprising a cylinder, a piston within said cylinder, an inlet passage communicating with said cylinder and adapted to conduct a hydro-carbon mixture to said cylinder, and an exhaust passage communicating with said cylinder and adapted to conduct the burned gases from said cylinder, said exhaust passage being provided with a tubular head extending into said inlet passage and longitudinally thereof.

5. An internal combustion engine, comprising a cylinder, a piston in said cylinder, inlet and exhaust passages communicating with said cylinder through a port, a reciprocating valve member adapted to open and close said port and provided with a hollow passage through which a hydrocarbon mixture is conducted, and a tubular head communicating with said exhaust passage and extending longitudinally of said passage of the valve and spaced from the surface thereof.

6. An internal combustion engine, comprising a cylinder, a piston within said cylinder, inlet and exhaust passages communicating with said cylinder, said exhaust passage extending transversely of and adjacent one end of said inlet passage and provided with a tubular head extending axially into said inlet passage and substantially throughout the same.

7. An internal combustion engine, comprising a cylinder, a piston within said cylinder, an inlet valve chamber arranged in parallel relation to said cylinder, a port connecting said inlet chamber and said cylinder, a valve member in said chamber acting to open and close said port, an exhaust passage communicating with said cylinder and extending transversely of said inlet chamber, and provided with a tubular head communicating with said exhaust passage and projecting into said inlet chamber and beyond said port.

8. An internal combustion engine, comprising a cylinder, a piston within said cylinder, an inlet passage arranged in parallel relation to said cylinder and provided adjacent one end thereof with a port communicating with said cylinder, a hollow valve member acting to open and close said port, an exhaust passage communicating with said cylinder and extending transversely of and adjacent to one end of said inlet passage and provided with a tubu-

lar head in open communication with said passage and extending axially into said inlet passage and said valve member.

9. An internal combustion engine, comprising a cylinder, a piston within said cylinder, an inlet passage arranged in parallel relation to said cylinder and provided with a port communicating with said cylinder, a hollow valve member provided with an opening at one end thereof, means for moving said valve member to open and close said port, an exhaust passage communicating with said cylinder and extending transversely of and adjacent to the upper end of said inlet passage, and provided with a tubular head communicating with said exhaust passage and depending into said inlet passage and the open end of said valve member.

10. An internal combustion engine, comprising a cylinder, a piston in said cylinder, inlet and exhaust passages arranged in parallel relation and communicating with said cylinder, an exhaust pipe communicating with one end of said exhaust passage and extending transversely of the adjacent end of said inlet passage, and said pipe being provided with a tubular head communicating with said exhaust pipe and projecting longitudinally into and extending substantially throughout the length of said inlet passage.

11. An internal combustion engine, comprising a cylinder, a piston in said cylinder, inlet and exhaust passages arranged in parallel relation to each other and to said cylinder, said passages being open at their exhaust ends and provided with ports communicating with said cylinder, an exhaust pipe communicating with the open end of said exhaust passage and extending transversely over the open end of said inlet passage and forming a closure therefor, said pipe being provided with a tubular head communicating with said exhaust pipe and projecting longitudinally into said inlet passage and extending beyond said port.

12. An internal combustion engine, comprising a plurality of cylinders, pistons in said cylinders, gas inlet and exhaust passages associated with each of said cylinders, an exhaust manifold communicating with each of said exhaust passages, and provided with a plurality of tubular heads communicating at one end with said exhaust manifold and closed at their outer ends, one of said tubular heads extending into each of said inlet passages.

13. An internal combustion engine, comprising a plurality of cylinders, pistons in said cylinders, inlet and exhaust passages associated with each of said cylinders and arranged in parallel relation, and an exhaust manifold communicating with each of said exhaust passages and extending transversely

of said inlet passages, said exhaust manifold being provided with a plurality of hollow heads, each communicating with said manifold and arranged to project into one of said inlet passages.

14. An internal combustion engine, comprising a cylinder casing having a plurality of cylinders therein, pistons in said cylinders, gas inlet and exhaust passages associated with each cylinder, all of said passages extending parallel with said cylinders and with each other, the upper ends of said passages opening through said cylinder casing, and an exhaust manifold mounted on top of said cylinder casing and over the open ends of said passages, said manifold communicating with each of said exhaust passages and forming a closure for the open ends of said inlet passages, and provided with a plurality of integral hollow heads, each depending into one of said inlet passages.

15. An internal combustion engine, comprising a cylinder, a piston in said cylinder, a crank shaft connected with said piston, an inlet valve chamber communicating with said cylinder, a hollow cylindric valve member mounted in said inlet valve chamber and driven from said crank shaft and provided with an opening at one end thereof, an exhaust pipe communicating with said cylinder and extending transversely of said inlet valve chamber adjacent the open end of said valve member, said pipe being provided with a tubular head extending axially into said valve member.

16. An internal combustion engine, comprising a cylinder, a piston within said cylinder, a crank shaft connected with said piston, inlet and exhaust valve chambers adjacent to and communicating with said cylinder, a hollow cylindric valve member mounted in said inlet valve cylinder and driven with a reciprocating movement from said crank shaft, said valve member being provided with a passage therethrough opening at one end of the valve into said valve chamber, an exhaust pipe communicating with said exhaust valve chamber, and a hollow head communicating with said exhaust pipe and extending axially into said passage of the inlet valve member.

17. An internal combustion engine, comprising a cylinder, a piston within said cylinder, a crank shaft connected with said piston, inlet and exhaust valve chambers communicating with said cylinder, valve members of the reciprocating sleeve type mounted in said valve chambers and driven from said crank shaft, said inlet valve member having a central passage open at one end and a port at its opposite end adapted to communicate with a source of hydrocarbon supply, an exhaust pipe communicating with said exhaust valve chamber and extending

transversely of said inlet valve chamber, and provided with a hollow head integral with said exhaust pipe and extending axially into said passage of the inlet valve, said head having a diameter less than the diameter of said passage.

In testimony that I claim the foregoing as

my invention, I affix my signature in the presence of two witnesses, this 19th day of May, A. D. 1916.

CLAYTON E. FREDERICKSON.

Witnesses:

CHAS. H. POOLE,

CLARA L. PEOPLES.
